(57) **CLAIM**

The ornamental design for a mounting device, as shown and described.

DESCRIPTION

FIG. 1 is a perspective view of a mounting device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a perspective view thereof in use; and,

FIG. 9 is another perspective view thereof in use.

Broken lines are included herein for illustrative purposes only and form no part of the claimed design.
